E. Wagner.

UNITED STATES PATENT OFFICE.

JOSEPH H. DOWNS, OF FORT WAYNE, INDIANA.

SIGNAL-CONTROL APPARATUS.

Application filed November 20, 1923. Serial No. 675,900.

To all whom it may concern:

Be it known that I, JOSEPH H. DOWNS, a citizen of the United States, residing at Fort Wayne, in the county of Allen and 5 State of Indiana, have invented certain new and useful Improvements in Signal-Control Apparatus, of which the following is a specification.

This invention relates to a signal control apparatus and particularly to a construction adapted to complete a signal circuit and maintain the same for a predetermined time after which the circuit is automatically broken to release or relieve the signal. 10

Previous devices of this character have been adapted to retard the breaking of the circuit but did not provide for the cooperation of signal circuit makers at opposite sides of a crossing with an intermediate circuit breaker timed in its action to maintain an open circuit until a car passes over the second circuit maker. 15

The invention has for an object to provide a novel and improved construction in which circuit breakers are disposed at opposite sides of the crossing and provided with means to maintain the circuit until the car reaches the crossing where a circuit breaker is disposed and has retarding means to 20 maintain an open circuit until the circuit maker has been restored to a similar position.

Another object of the invention is to provide a novel and improved construction of circuit maker or breaker comprising a tensioned actuating lever connected to a piston disposed within a cylinder which has an intake check valve and an adjustable outlet valve, said piston carrying one member 35 of a circuit contact disposed to contact with a cooperating member supported by the cylinder.

Other objects and advantages of the invention will be hereinafter set forth and 45 the novel features thereof defined by the appended claims.

In the drawings:

Figure 1 is a side elevation showing the invention applied; 50

Figure 2 is a similar view of one of the circuit makers with the cylinder members in section;

Figure 3 is a like view of the circuit breaker; and

Figure 4 is a detailed section on line 4—4 of Figure 3.

Like reference characters designate corresponding parts throughout the several figures of the drawing.

This invention is adapted for application 60 to either a single or double track railway system and for operation by the flange of a car wheel or other member carried by a moving vehicle. In the application of the invention illustrated it is applied to a single 65 track railway with the circuit makers disposed at opposite sides of a crossing and the circuit breaker intermediate thereof at approximately the crossing point.

The numeral 10 designates the rails, and 70 at one side thereof a flat spring member 11 is secured at one end 12 and adapted to contact with a sliding plunger 13 which is limited in its upward movement by a flange or collar 14 and pivotally connected at its 75 lower end to a lever 15 suspended by a link 16 from a suitable support, as at 17. This lever is pivoted at its outer end 18 to a rod 19 extending from a piston 20 disposed within a cylinder 21 which is provided at 80 its lower portion with an intake pipe 22. This pipe is provided with an intake check valve 23 of any desired character, for instance comprising a spring-pressed ball 24 as shown in Figure 3, and is also provided 85 with a needle valve 25 adjustably mounted in a casing 26 to control the outlet from said cylinder and thereby establish the timing for the restoring movement of the piston and the consequent period within which the 90 circuit is maintained.

The circuit contact members may comprise an elongated arm 27 supported by a lateral bracket 28 from the upper end of the piston rod 19 and adapted to cooperate 95 at its lower portion 29 with a contact plate 30 mounted upon the cap 31 for the cylinder 21. A suitable circuit wiring 32 extends to this plate 30 and a wiring 33 to the arm 27 at its mounting upon the bracket. 100

The lever 15 may be provided with any suitable tensioning means, a desirable form being the weights 34 adjustably suspended therefrom by means of the apertures 35 in the lever so that the weights may be shifted relative to the fulcrum of the lever and the number thereof varied at will. 105

The construction of the circuit breaker

is substantially the same as that described in connection with the circuit maker with the exception that the bracket arm 28 from the piston 19 carries a blade 36 cooperating with opposite contacts 37 mounted upon the plate 38 carried by the cylinder cover 31 to form a knife switch. This blade 36 may be provided with a conducting covering 39 insulated therefrom as shown at 40 in Figure 4.

In the form of the invention shown, two contacts cooperate with this blade, one controlling each of the circuit makers and the lines 32 and 33 from these makers extend to these contacts so as to control both of the circuit makers through the single circuit breaker. From the line 32 a line 41 extends to a signal device of any desired character while a similar line 42 extends from the line 33 through a battery 43 or other source 20 of power to the signalling mechanism.

In the operation of the invention it will be seen that a car approaching from the right will depress the spring and plunger, lifting the lever as indicated by dotted lines 25 in Figure 1, thus raising the piston and producing an intake of air within the cylinder. As soon as the wheel passes from the track spring the weight upon the lever begins a restoring movement thereof and the circuit contacts are at that time in engagement establishing the signal circuit. The period required for the escape of the air or fluid pressure from the cylinder is determined by the adjustable regulating valve 35 and the circuit maintained for such period unless sooner broken by the circuit breaker disposed at the crossing. This circuit breaker being engaged by the flange of the car wheel operates in a similar manner to the circuit makers but breaks the circuits to both thereof so that if the circuit maker first actuated has not been restored to open circuit position the circuit will be broken and the signal released as soon as the car passes the crossing. The circuit breaker is timed for a retarding operation sufficiently long to permit the restoring movement of the circuit maker and consequently the car in passing over the second circuit maker has no effect 40 upon the circuit to the signal mechanism and this second circuit maker is operated and restored without affecting the circuit which is held open during that period.

It will be seen that the invention provides 55 a simple, efficient and economically manufactured apparatus for controlling a crossing signal from either direction of travel and preventing any repeated operation thereof by a car after passing the crossing point. The construction of the circuit makers and breakers is such that the retarding action 60 may be definitely adjusted so that the period during which the circuit is maintained to the signal may be absolutely determined.

65 While the invention is shown as applied

to a single track, it will be apparent that one of the circuit breakers may be located upon a second track so that the signal operation is controlled from both directions and subject to the definite release of the circuit breaker 70 at the crossing point.

While the specific construction of the circuit arrangement has been shown and described, still the invention is not confined thereto as changes and alterations may be 75 made without departing from the spirit of the invention as defined by the appended claims.

Having thus described my invention, what I claim as new and desire to secure by Letters Patent is:

1. In a signal control apparatus, a circuit maker, a device disposed for actuation by a vehicle wheel to establish circuit to a signal mechanism, a circuit breaker connected to control said signal circuit, means for actuating said breaker by the wheel of a vehicle, and means for retarding the movement of said circuit breaker to control the action of 80 said circuit maker.

2. In a signal control device, a circuit maker comprising contacts adapted to maintain circuit to a signal device for a predetermined time, means adapted for actuation by a wheel for establishing said circuit and means to regulate the retarding action for breaking said circuit, and a circuit breaker connected to said circuit maker to control the circuit therefrom and having retarding means to maintain an open circuit until the 90 circuit maker is restored to initial position.

3. In a signal control device, a plurality of circuit makers each adapted to be actuated by a car wheel, means for retarding the restoring movement of said circuit makers, an intermediate circuit breaker connected in circuit with each of the circuit makers, means for actuating said circuit breaker by a car wheel, and timed means for retarding the circuit breaker to maintain 100 an open circuit during the passage of the wheel over a successive circuit maker.

4. In a signal control device, a plurality of circuit makers, means for actuating the same by a car wheel, an intermediate circuit breaker comprising a piston and cylinder, means for actuating said piston in one direction by a car wheel, means for retarding the restoring movement of said piston, contact members connected in circuit with each 110 of the circuit makers, and a cooperating contact blade carried by said piston to engage said contacts.

5. In a signal control apparatus, a cylinder and piston, an intake for said cylinder 125 having an inlet check valve and an adjustable outlet valve, a contact member carried by the rod of said piston, a cooperating contact supported upon said cylinder, and means for actuating said piston by a car wheel. 130

6. In a signal control apparatus, a cylinder and piston, an intake for said cylinder having an inlet check valve and an adjustable outlet valve, a contact member carried by the rod of said piston, a cooperating contact supported upon said cylinder, a pivoted lever connected to said piston, a plunger at one end of said lever, and a spring contact disposed above said plunger.
- 10 7. In a signal control apparatus, a cylinder and piston, an intake for said cylinder having an inlet check valve and an adjustable outlet valve, a contact member carried by the rod of said piston, a cooperating contact supported upon said cylinder, a pivoted lever connected to said piston, a plunger at one end of said lever, and an adjustable weight mounted upon said lever.
- 15 8. In a signal control apparatus, a cylin-

der provided with intake and outlet valves, 20 a piston disposed therein and provided with a rod, a bracket projected laterally from said rod, means for actuating said rod from a track device, and circuit contacts comprising a depending arm carried by said bracket 25 and disposed parallel to a cooperating plate supported by said cylinder.

9. In a signal control apparatus, a cylinder provided with intake and outlet valves, 30 a piston disposed therein and provided with a rod, a bracket projected laterally from said rod, means for actuating said rod from a track device, and a knife switch member carried by said bracket and disposed to cooperate with opposite contacts supported 35 from said cylinder.

In testimony whereof I affix my signature.

JOSEPH H. DOWNS
